UNITED STATES PATENT OFFICE.

HARRY W. HARDINGE, OF NEW YORK, N. Y.

APPARATUS FOR DISINTEGRATING ORES AND OTHER MATERIALS.

No. 908,861.

Specification of Letters Patent.

Patented Jan. 5, 1909.

Application filed December 6, 1907. Serial No. 405,368.

To all whom it may concern:

Be it known that I, HARRY W. HARDINGE, a citizen of the United States, residing at New York, in the county and State of New 5 York, have invented a certain new and useful Improvement in Apparatus for Disintegrating Ores and Other Materials, of which the following is a specification.

In grinding mills as in all other apparatus 10 the work applied for the production of a desired result should, in general, be as little as possible greater than the work theoretically required for the result; but however much designers of ore-reducing mills may have 15 striven for this balance or proportion of work done to power applied, I have not found, in the course of an extended experience with probably all types of ore-reducing apparatus in practical use, mills whose performance, 20 all things considered, is comparable in efficiency to that desired. Furthermore, it is in general desirable that the particles of the disintegrated material should all be within reasonably narrow limits as to size; but in 25 the mills with which I am familiar it is found in practice that in reducing all the material to the upper limit of desired size a considerable proportion, even as much as seventy per cent., is reduced to much below the desired 30 lower limit. It is also difficult and in some apparatus impossible to reduce a given material to a size of particles different from that for which the apparatus is designed.

In my copending application, filed of even 35 date herewith, I have described and claimed broadly a novel method which I have devised for reducing or disintegrating ores and like materials without such drawbacks as the above. In practicing that method the lumps 40 or pieces of ore or other material are subjected to tumbling action, (either with or without the addition of non-friable crushing or grinding bodies, such as metal balls, flint pebbles, etc.), whereby the lumps or pieces 45 are broken up by impact and attrition, in a succession of reducing or grinding zones of gradually diminishing reducing action, and maintaining a substantial vertical stratification of the material according to the size of 50 its pieces or particles. Stated a little differently, the material is passed through a succession of reducing zones of successively less reducing action, according as, or as fast as, the lumps or masses of the material are 55 broken up or disintegrated. In this way the pieces of material are subjected to reducing

actions which are substantially proportionate respectively to the sizes of the pieces and hence, in general, to the work required to break them up. In other words, the reducing action exerted on a given piece or lump is substantially in proportion to the work required. The piece or lump being thus broken up, its parts promptly move forward to the next zone of reduction, and so on till the desired 60 disintegration is reached.

The ultimate size of the particles, to which a given material is reduced, depends, in general, upon the amount of impact and attrition to which the material is subjected. 70 This is best regulated by varying the number of reducing zones, or the rate of passage of the material therethrough, or both, as will be more fully explained hereinafter.

The chief object of my present invention 75 is to provide a simple and convenient apparatus capable of performing the operations above outlined. In the apparatus which I have devised for the purpose I provide a tumbling barrel, rotatable about an axis arranged in a general horizontal direction, although the axis may if desired be tilted to various degrees of inclination to the horizontal for the purposes hereafter described. This barrel is provided with an inlet opening 80 of suitable character, through which the material to be treated is introduced, and with an outlet opening at the axis of the barrel through which the ground or disintegrated material is discharged. It is essential that 85 the shape or form of the barrel backward from the outlet opening be that of a cone, and that the said outlet opening be at the apex thereof. Backward from the base of this cone, which for convenience of terminology is 90 hereinafter referred to as the "conical outlet portion", or simply the "outlet portion", the barrel may be variously formed, for example cylindrical or conical or both. The inlet opening is in this portion, which therefore 95 may be appropriately termed the "inlet portion".

When the lumps or masses of ore or other material, with or without the addition of hard pebbles, metal balls, or other similar 105 non-friable crushing bodies, are introduced into such a barrel, a new and very striking result is produced. This result, however, will be more clearly understood and appreciated when described in connection with the 110 annexed drawings. Therein,

Figure 1 shows in side elevation a conven-

ient embodiment of the invention. Fig. 2 is a vertical longitudinal section of the barrel of Fig. 1, in which barrel the inlet portion as well as the outlet portion is conical. This figure also illustrates the peculiar result which is characteristic of my invention, to wit, the arranging of the pieces or bodies in the outlet portion of the barrel according to size, the pieces or bodies being successively 10 smaller toward the outlet opening. Fig. 3 is a vertical longitudinal section of the barrel of Fig. 1, but with its axis inclined to the horizontal. Fig. 4 is a cross-section on line IV—IV of Fig. 3. Figs. 5 to 10 are vertical 15 longitudinal sections of various different forms of barrels, embraced by my invention.

Referring now to Fig. 1, 1 indicates a tumbling barrel formed of two cones, 2, 3, placed base to base, and of different pitch, the slant 20 of cone 2 relative to its axis being greater than the slant of cone 3. The ends of the cones are open, at 4, 5, the former opening serving as the inlet, through which the material to be disintegrated is introduced, and the latter serving as the outlet, through 25 which the disintegrated material is discharged. The cone 2 may therefore, as previously stated, be appropriately termed the inlet cone or inlet portion, and the cone 3 the outlet cone or outlet portion. At the greatest 30 diameter of the barrel is a toothed annulus or gear-ring 6, with which meshes a pinion 7 on a shaft 8 carrying a pulley 9 by which the shaft 8 can be driven from any convenient 35 source of power, thereby rotating the barrel. For supporting the latter it is provided with bearing rings 10, 11, resting on bearing rollers on opposite sides of the barrel. Two of these rollers, on the same side of the 40 barrel, are shown at 12, 13. The bearings for the rolls 12, 13, and pinion 7 are mounted on a base 14, which in turn is supported on jacks 15, 16, so that either end of the base 45 can be raised and the other end lowered, thereby varying the inclination of the axis of the barrel to the horizontal. To permit such 50 tilting the shaft 8 is provided with a universal joint 17 adjacent to the pinion 7. By proper manipulation of the jacks the universal joint can be made the center on which the barrel tilts.

Referring now to Fig. 2, which shows the barrel in section, with material undergoing treatment, it will be seen that, the axis of 55 the barrel being horizontal or substantially so, the lower side, $a-b$, of the outlet portion, makes a lesser angle with the horizontal than does the corresponding side $a-c$ of the inlet portion. Hence the masses or lumps of 60 material (introduced through the inlet opening 4), in the inlet portion rest on a steeper incline than the pieces or lumps in the outlet portion. In consequence the former masses have greater tendency to seek the lowermost 65 part of the barrel than do the masses in the

outlet cone, the incline of which is less steep. Furthermore, the larger masses, having greater weight and correspondingly greater momentum, also cause the same to tend constantly to displace from the lowest point 70 of the barrel the smaller pieces, which have less weight and correspondingly less momentum. The result is that the larger masses collect in the central transverse zone of the barrel, displacing the smaller and lighter 75 masses up the lesser incline of the outlet cone. It will be seen that the loose, freely movable crushing bodies d are at the center of the barrel. As the barrel rotates these balls or pebbles together with masses or 80 lumps of the material undergoing treatment are carried up the ascending side of the barrel and finally fall back with considerable force upon the remaining material. The material is thus broken up into smaller pieces 85 by impact as well as by attrition, and these smaller pieces, as fast as they are formed, are by the remaining larger bodies and by those entering from the inlet opening displaced toward the outlet opening 4. Beyond the 90 zone of the crushing balls a similar operation takes place, the material being further broken up by the mutual impact and attrition of the lumps and the resulting smaller pieces being always displaced up the incline 95 toward the outlet. The material thus arranges itself as shown in Fig. 2, the pieces or lumps being successively smaller toward the outlet, until ultimately the fully disintegrated 100 material passes out of the barrel through the opening 4, and thus there is a constant progression of material, as fast as it is broken up, from inlet to outlet; that is, when a lump is broken up, its pieces are caused to move forward to the zone of similarly sized pieces, and 105 as these are broken up their particles are themselves caused to move forward, and so on till the outlet is reached. In this connection it is to be remembered that the lumps have no substantial travel forward until and 110 except as they are reduced to smaller pieces. For example, the non-friable crushing balls d , Fig. 2, remain in a comparatively narrow transverse zone, as shown. Consequently 115 the result is, in general, that large masses act upon large mass, small masses upon small; and as fast as lumps are broken up they are displaced to the succeeding zone, making room for lumps from the preceding zone. It will therefore be seen that where 120 the greatest crushing or reducing action is needed, to wit, in breaking up the large lumps, there the lumps and crushing bodies have the longest fall and hence the heaviest impact and greatest attrition; while the 125 smaller bodies, which require less reducing action, have less fall and hence less impact and attrition. This means that the power which drives the cone is efficiently applied; since the smaller bodies lie nearer the apex 130

of the cone, and hence are lifted a shorter distance and on a shorter radius, requiring less power, than the heavier or larger masses which lie farther from the apex and hence 5 are lifted a greater distance and on a larger radius. The economy thus effected is very marked. In fact, it has been found that the power required is only about one-third that required by a cylindrical tubemill having the 10 same output.

The peculiar arrangement of the material in the barrel according to size can perhaps best be described as a sort of "vertical stratification". In the apparatus under consideration, 15 the vertical strata are the reducing zones of my process, previously referred to, and the transfer of material from one zone to the other, toward the outlet, as required by my process, is effected as above described. 20 It will also be seen that in the barrel 1 the reducing zones have successively less reducing action, by reason of the successive diminution of the size of the pieces or lumps in the zones; and by reason of the lessening depth 25 and width, or in general the extent, of the zones, whereby the pieces or masses have less tumbling or agitation as the barrel rotates.

As previously stated, the size of particles to which the material is finally reduced can 30 be readily regulated by varying the number of reducing zones. In the apparatus under consideration this can easily be done by tilting the axis of the barrel so as to vary the inclination of the side $a-b$ to the horizontal. 35 Thus if the barrel be tilted so that the outlet is lower, as in Fig. 3, all the reducing zones will be displaced toward the outlet, and those nearest the outlet will be crowded, so to speak, out of the barrel, with the result that 40 larger particles will reach the outlet. Reversing the inclination of the axis will have the contrary effect. In general I prefer to so proportion the outlet cone that with the axis horizontal the particles discharged will 45 be the smallest that may be desired, and then produce the size that may be desired in any particular case by lowering the outlet more or less. The tilting of the barrel also modifies, to a certain extent, the manner in which 50 the material is caused to progress from zone to zone. Thus, when the barrel is rotated on an inclined axis (represented by the dotted line $e-f$, Fig. 3) the pieces of material are carried up the ascending side of the barrel in 55 lines perpendicular to the axis and inclined to the vertical, for instance in lines parallel to those indicated at g, g , Fig. 3; but when the pieces are disengaged from the side of the barrel they fall in vertical lines, as those indicated at h, h , and hence strike the material at 60 points proportionally nearer the outlet. But since the surface of the material is inclined, being higher at the ascending side than at the descending side, as indicated in Fig. 4, all 65 the pieces falling from the ascending side tend

to roll down to the lower parts of the barrel, for example toward the point i , in paths or lines as indicated by the curved lower portions of the dotted lines h, h , in Fig. 3; and the larger and heavier the pieces the farther 70 they roll toward the point i . This carrying forward of all the pieces as they are raised on the ascending side of the barrel, and their subsequent backward travel in proportion to their different sizes, materially aids the 75 displacing action which has been previously described herein and which constantly urges the material forward.

Barrels of other forms than that illustrated in Figs. 1 to 4, may be employed. For example, there may be a cylindrical portion between the two cones, as in Fig. 5. Or the inlet portion may be a short cylinder as in Fig. 6, a flat disk as in Fig. 7, or a rounded or bulging disk as in Fig. 8. In these figures the arrangement of the material in the barrel is indicated diagrammatically. Still other forms are illustrated in my copending application Serial No. 315,858, filed May 9, 1906. In the latter mentioned forms the inlet and outlet portions are equal cones placed base to base as in Fig. 9, or with a short cylindrical part between the two, as in Fig. 10. In all the forms, however, I find that the slant of the lower side of the outlet cone relative to 95 the perpendicular, or direction of gravity, should be not less than about 45° nor greater than about 70° . The slant of the inlet cone, when one is used, should, in general, be not less but preferably greater than that of the 100 outlet cone. The length of the cylindrical portion, when one is used, depends in great measure upon the nature of the material to be disintegrated. Thus a very hard ore may 105 make a longer cylindrical part desirable or necessary, so as to accommodate a greater number of crushing balls, while for a softer material a barrel like that shown in Fig. 7 may be sufficient. In other words, the size and proportions of the barrel depend in general upon the number and extent of the reducing zones needed for a desired extent of 110 reduction of the given material.

Practical use of my invention has shown for it a very marked utility. The small 115 power required in proportion to output makes its efficiency higher than that of any other apparatus with which I am familiar, while the ease with which the extent of reduction can be regulated, and the uniformity 120 of the ultimate particles of the material as to size, are features of indisputable value.

As previously stated, crushing bodies, for example balls or pebbles, may or may not be used, depending in large measure on the 125 friability of the material to be disintegrated. This material which is comparatively soft or friable may be sufficiently disintegrated without the assistance of balls or pebbles, but they may be used if desired, and may be 130

necessary where relatively hard material is to be reduced. In the appended claims "crushing bodies" are included as an element of the combination, but it is to be understood that these bodies may, as just stated, be the lumps or masses of ore or other material undergoing treatment, or the metal balls, flint pebbles, etc., referred to above. In the former case the "crushing bodies" are of course themselves disintegrated, but they are constantly replaced by fresh material.

If desired, a current of water may be kept flowing through the barrel during the operation thereof. The water will facilitate the forward travel of the finer particles, particularly those which may be formed in the parts of the barrel not adjacent to the outlet.

What I claim is:

20 1. In apparatus for disintegrating ores and other materials, in combination, a tumbling barrel comprising a conical inlet portion having an inlet opening, and a conical outlet portion joined at its base to the inlet portion and provided at its apex with an outlet opening; a multiplicity of crushing bodies freely movable inside the barrel; and means for supporting the barrel for rotation about its longitudinal axis and with its said axis inclined to the horizontal.

25 2. In apparatus for disintegrating ores and other materials, a tumbling barrel comprising a conical inlet portion having an inlet opening, and a conical outlet portion joined at its base to the inlet portion and provided at its apex with an outlet opening; a multiplicity of crushing bodies freely movable inside the barrel; and means for supporting the barrel for rotation about its longitudinal axis and with its said axis inclined to the horizontal.

3. In apparatus for disintegrating ores and other materials, in combination, a tumbling 45 barrel comprising an inlet portion having an inlet opening, and a conical outlet portion joined at its base to the inlet portion and provided at its apex with an outlet opening; a multiplicity of crushing bodies freely movable inside the barrel; and means for supporting the barrel for rotation about its longitudinal axis and with its said axis inclined to the horizontal.

4. In apparatus for disintegrating ore and other materials, in combination, a tumbling barrel comprising an inlet portion having an inlet opening, and a conical outlet portion joined at its base to the inlet portion and provided at its apex with an outlet opening; a multiplicity of crushing bodies freely movable inside the barrel; means for supporting the barrel for rotation about its longitudinal axis; and means for varying the inclination of the said axis of the barrel to the horizontal.

5. In apparatus for disintegrating ores and other materials, in combination, a tumbling barrel comprising an inlet portion having an opening for the introduction of material to be disintegrated, and a conical outlet portion joined at its base to the inlet portion and provided at its apex with an opening for the discharge of disintegrated material, the slant of the lower side of the said conical outlet 75 portion relative to the perpendicular or direction of gravity being not less than 45° nor more than 70°, approximately; a multiplicity of crushing bodies freely movable inside the barrel; and means for supporting the barrel 80 for rotation about its longitudinal axis.

HARRY W. HARDINGE.
